PUMP

Filed Jan. 30, 1929

INVENTOR:

JOHN THOMAS BILDERBECK,
By Otto de Ringer,
his Atty.

UNITED STATES PATENT OFFICE

JOHN THOMAS BILDERBECK, OF LOS ANGELES, CALIFORNIA, ASSIGNOR TO WESTERN CONCRETE PIPE COMPANY, OF LOS ANGELES, CALIFORNIA

PUMP

Application filed January 30, 1929. Serial No. 336,108.

This invention relates to devices designed to actuate a number of pumping plungers by means of a rotating head.

One of the objects of this invention is to design the rotating head with a slanting face in axial direction to contact with and slidably ride over a number of pumping plungers, the pumping plungers being yieldingly mounted by means of springs against the tension of which the plungers are pressed by the rotating head so that the plungers automatically move in one direction against the head by means of the springs.

Another object is to provide a sectional head of which one section can be adjusted with respect to its actuating front face in relation to the other section.

Another object is to provide a pivotal inter-connection between the sections of the actuating head.

Another object is to provide adjusting means by which the valves and plungers can be controlled from zero to 100% pumping and acting movements.

Another object is to provide a pump of this type in which the actuating head and the plungers are incased in a lubricant holding chamber.

Another object is to provide communications between the lubricant chamber and the working side of the plungers whereby the lubricant in the pump chamber can be used for producing a desired pressure on the discharging end of the pump.

Another object is to provide a pump operating under constant speed and designed to deliver a variable volume.

Other objects will appear from the following description and appended claims as well as from the accompanying drawings, in which—

Fig. 1 is a general longitudinal midsectional view of a simple pump structure with a revolving actuating shaft and an also revolving actuating head provided with an axially inclined adjustable contact means between the actuating head and a plurality of axially movable valves yieldingly contacting with the head for continuous pumping movements and the several parts incased in a lu-

bricant holding chamber according to this invention.

Fig. 2 is a top plan view of the actuating head seen in the direction of the arrow 2 in Fig. 1.

Fig. 3 is a cross section through the adjustable head on line 3—3 of Fig. 2.

Fig. 4 is a fragmentary top plan view of the base block in small scale roughly outlining a plurality of plunger holes arranged in a circle and other holes by which this base block is connected with other parts of the pump.

As illustrated a base block 5 is provided with an upwardly projecting central pin 6. This block is also provided with a plurality of plunger holes 7 and bolt holes 8.

A plunger 9 is mounted in relation to each plunger hole 7. The plunger is provided with an enlarged head 10 facilitating an insertion of a spring 11 between the head 10 and the block 5 whereby the plunger is automatically lifted for suction operations.

The spring actuated plungers are disposed to contact with an adjustable cross head. The cross head consists principally of two pivotally connected members 12 and 13, the pivot being indicated at 14.

A special ball bearing consisting of the plates 15 and 16 with balls 17 inserted between the plates 15 and 16 is disposed between the cross head and the top of the plungers, to reduce the friction between the cross head and the plungers. The cross head is turnably mounted with its hollow shaft 18 in the top block 19 and is geared or operatively connected to the crosswise extending driving shaft 20, a ball bearing 21 being inserted between the cross head and the top block 19 to reduce the friction between the cross head and the top block 19.

Adjustability is accomplished between the members 13 and 12 of the cross head by a spindle 22 disposed through the hollow of the shaft 18 and through the central hollow of the upper member 12 so that the lower end 23 of the spindle contacts with the lower member 13 of the cross head.

The spindle is sectioned to allow an insertion of the ball 24 whereby the friction be-

tween the comparatively stationary top section 22, of the spindle and the lower section 22, of the spindle is reduced.

A controlling lever 25 and a lock member 26 are provided on the upper end of the spindle 22.

The lower member 13 of the cross head can be adjusted from the slanting position in which it is illustrated and which involves the largest stroke of the plungers to a position to bring the front face of the ball bearing plates to a practically horizontal position, or, in other words, to a position squarely crosswise to the axis of the whole structure and the axes of the plungers.

This adjusting of the cross head and especially of the lower member 13 including the plates 15 and 16 is accomplished by a turning of the spindle 22 so that the plungers may be controlled from an extreme long stroke to absolutely inoperative position.

In Fig. 1, for instance, the plunger head 10, in the left hand side of the drawings, is shown in its topmost or extreme outermost position while in dotted lines indicated at 10₄ the lowermost position of the same plunger head is indicated. The movements of the several plungers are utilized to actuate or control the check valves 27 and 28.

An outward movement of the plunger 9 results in an opening of the valve 27 and in a drawing of a medium into the compartment 29.

A downward stroke of the plunger results in an automatic closing of the valve 27 and in an opening of the valve 28 whereby a medium is discharged in the direction of the arrows 30.

All the several parts disposed between the base block 5 and the top block 19 are incased as indicated at 31 so that a lubricant can be maintained within this casing around all the several working parts. This lubricant can also be used as a pumping medium to be drawn through the openings 32 in the direction of the arrows 33 past the valves 27 into the compartment 29.

An inlet connection 34 is provided on the casing 31 whereby a lubricant or similar pumping medium can be supplied in a required amount to maintain sufficient of this medium within the casing to facilitate the proper operation of this pump.

The connection 34, of course, can be used to serve as a suction connection for this pump to draw any material that may be drawn by any pump, and the discharging connection 35, of course, may be used for discharging any material in any customary manner. However, this pump is especially suited for producing a high pressure on a variable capacity of from zero to 100%.

Since the pump operates continuously and since a plurality of valves or plungers can be installed, depending only on the size of

the pump and the size of the plungers, it must be understood that this pump can be made as a non-pulsating apparatus.

It, furthermore, must be understood that at a constant speed the volume to pass through the pump can be varied at the will of the operator.

Having thus described my invention, I claim:

1. In a pump, a revolving head made in sections pivotally interconnected of which one section has a positive and permanent relation to the axis of the revolving head and the other section embodying an actuating face adapted to be moved from a plane practically at right angles and crosswise to the longitudinal axis of the revolving head to a slanting position, and pumping plungers disposed to move in the direction of the axis of the revolving head and so as to contact with the end face of the revolving head, the sectioned head being adjustable with respect to its pivot interconnection whereby the length of the stroke of the plungers can be controlled.

2. In a pump, a revolving head made in sections pivotally interconnected of which one section has a positive and permanent relation to the axis of the revolving head and the other section embodying an actuating face adapted to be moved from a plane practically at right angles and crosswise to the longitudinal axis of the revolving head to a slanting position, pumping plungers disposed to move in the direction of the axis of the revolving head, and adjusting means for the sectioned cross head whereby the length of the stroke of the plungers can be controlled.

3. In a pump, a sectioned revolving head having a shaft portion whereby the head is turnable around a longitudinal axis of the shaft portion, one of the sections having a positive and permanent relation to said axis and another section being pivotally connected to said first section of the head and adapted to be adjusted from a plane at right angles and crosswise to the longitudinal axis of the shaft portion to a slanting position.

4. In a pump, a sectioned operating head of which one member is pivotally connected to the other member embodying an actuating face adapted to be disposed at right angles crosswise to the axis around which the operating head is mounted to turn, pumping mechanisms disposed to contact with said actuating face to be operated thereby when the head revolves, and adjusting means for controlling the pivotally connected members of the cross head so as to adjust the length of the stroke of the pumping mechanisms.

5. In a pump, pumping mechanisms disposed to operate in the direction of the lon-

- gitudinal axis of the pump, a sectioned operating head including one member pivotally connected to another member with an actuating face adjustably transversely to the longitudinal axis of the pump, controlling means for setting one of said members in relation to the other whereby the pumping mechanisms can be controlled in the operations from zero to 100% capacity.
6. In a pump, pumping mechanisms disposed to operate in the direction of the longitudinal axis of the pump, an adjustable cross head mounted to turn around the longitudinal axis of the pump, a flat-disc ball bearing disposed with one flat disc abutting against the cross head and another flat disc forming the abutting face for the pumping mechanisms, and adjusting means for the adjustable cross head whereby the pumping mechanisms can be controlled from zero to 100% capacity.
7. In a pump, pumping mechanisms disposed to operate in the direction of the longitudinal axis of the pump, an adjustable cross head mounted to turn around the longitudinal axis of the pump, a flat-disc ball bearing disposed between the cross head and the pumping mechanisms, adjusting means for the adjustable cross head whereby the pumping mechanisms can be controlled from zero to 100% capacity, and a casing forming a chamber around the cross head and the pumping mechanisms and having communication with the pumping mechanisms whereby a pumping medium can be circulated through the chamber and through the pumping mechanisms as well as around the pumping mechanism and head to directly contact therewith.
8. In a pump, a plurality of plungers arranged in a circular manner and to operate in the direction of the longitudinal axis of the pump, a base block for the plungers, check valves in the base block in operative relation to the plungers, an adjustable operating head mounted to turn around the axis of the pump embodying one member pivotally connected to another member and having an actuating front face disposed adjustably transversely to the longitudinal axis of the pump, controlling means whereby the adjustable head can be set to operate the pumping plungers from zero to 100% capacity, operating means for the operating head, and a casing forming a chamber around the operating head and the plungers and having communication through the base block checkable by the said valves whereby a pumping medium can be circulated directly contacting with the several above-named parts through the casing and through the base plate.

In testimony that I claim the foregoing as my invention I have signed my name.

JOHN THOMAS BILDERBECK.
